UNITED STATES PATENT OFFICE.

THOMAS VAN AERNAM, OF ALBANY, NEW YORK.

WEAR-PLATE FOR WAGON-BOLSTERS.

SPECIFICATION forming part of Letters Patent No. 270,918, dated January 23, 1883.

Application filed October 13, 1882. (No model.)

To all whom it may concern:

Be it known that I, THOMAS VAN AERNAM, a citizen of the United States, and a resident of the city and county of Albany, in the State 5 of New York, have invented new and useful Improvements in Wear-Plates for Bolsters of Sand and other Wagons, of which the following is a specification.

My invention relates to wear-plates for bolsters of sand and other wagons in which the upper and lower wear-plates are made of chilled iron on their wearing sides, and combining the elements or devices hereinafter more particularly set forth and described.

15 The object of my invention is to provide wear-plates for bolsters and axles of wagons, which will have their wearing-surfaces of chilled-iron, capable of reducing the friction to a minimum as compared with the soft-iron plates 20 heretofore employed, and which will also have a chilled-iron circular engaging projection and recess made solid therewith about their king-bolt holes for relieving the king-bolt from strain, also increasing the vertical length of 25 the king-bolt holes in said plates, and relieving the strain of the plates on the attaching bolts and clips. I attain this object by means of the devices and elements illustrated in the accompanying drawings, in which similar letters of reference refer to similar parts throughout the several views.

In the drawings, Figure 1 represents a plan view of the axle wear-plates; Fig. 2, a plan view of the bolster wear-plates. Fig. 3 is a 35 cross-sectional view of said plates when joined and secured to their respective parts of the wagon. Fig. 4 is a sectional elevation of the same.

In the drawings, A represents the axle of 40 the wagon, and B the bolster. Heretofore it has been the practice to make wear-plates between said axle and bolster of soft wrought-iron and of uniform thickness throughout, with holes made central in the same for receiving king-bolts of large diameter. These 45 old forms of plates were secured from shifting on their respective parts of wagon by bolts or clips. The great disadvantages attending the use of said old form of wear-plates were their 50 excessive friction, which would cause them to wear rapidly away, so as to reduce the vertical

length of the king-bolt holes, and thereby cause the king-bolt to be rapidly cut at about its center of length, while at the same time this excessive friction would impose greater labor 55 on the animals when turning the fore part of the wagon. The excessive enlargement of the king-bolt holes and lessening of the diameter of the king-bolt would operate to permit the bolster to shift in relation to the axle, while 60 at the same time the heads of the bolts securing the plates to their respective parts of the wagon would be worn away and be drawn out of place, while the secure attachment of these old plates from shifting could not be had, as 65 the excessive friction attending their use would cause a dragging of one plate on the other and cause the plates to wear the wood and become loose. These disadvantages are wholly overcome and removed by my improved wear- 70 plates, which consist of the axle-plate C and bolster-plate D.

The axle-plate C consists of a cast plate having its upper or face side portions, a, made of chilled iron. Made central with said plate, 75 and in solid connection with the same, is a convex projection, b, surrounded by an annular step, c, both of which are also of chilled iron. The bush d is made central with the opposite side of said plate and solid with the 80 same. This axle-plate is pierced centrally through its convex projection b and bush d for forming the king-bolt hole e, of about one inch diameter. I prefer to make the chilled portion of said axle-plate about twelve inches long by 85 about five inches wide at its middle of length, and at the ends of said chilled portion is formed the transverse recess f for receiving clips g for securing said plates to the axle.

The bolster-plate D consists of a cast plate 90 having its upper or face side portion, a', made of chilled iron. Made central in the same is a concave recess, b', bounded by an annular recessed step, c', corresponding in size and form with the projection b and ring-step c, made 95 with the axle-plate. The metal of said recesses b' and c' are also of chilled iron. Made solid with said bolster-plate and with the side opposite from the recess b' is the bush d'. A central king-bolt hole, e', is provided, running 100 through bush d' and central with recess b', as shown. Countersunk holes f' are made in said

bolster-plate for receiving bolts g' for securing it to the bolster. The said wear-plates are each secured to their respective parts of the wagon—the axle-plate C to axle A by clasps g , and the 5 bolster-plate D to bolster b by bolts g' , as shown—and the king-bolt E is inserted in place, when the bolster will be coupled with the axle.

In practice the convexity of the projection 10 b and concavity of recess b' will operate to prevent sand or gritty substances from working in between the king-bolt hole and the king-bolt. The bushings d and d' increase the 15 length of the king-bolt holes, so as to greatly enlarge the extent of surface of the bores of said holes, so that the wear of the said holes and king-bolt will be greatly lessened. The projecting step c of plate C and the recessed step c' of plate D operate to relieve the king-bolt E from wear and transverse strain, and 20 transfer the friction from the king-bolt to the larger surfaces of said steps. The bushings d and d' operate with the recesses h and h' in the wood of the axle and bolster to relieve 25 the clasps and attaching-bolts of strain. The chilled face side portions of the said plate and their respective recesses and projections oper-

ate together to reduce the frictional wear to a minimum, and prevent the reduction of the king-bolt hole from the upper side of the bolster to the lower side of the axle, so that the king-bolt will, by its nut and head, hold the axle and bolster coupled together without liability of either of them canting or tipping, while at the same time they operate to reduce 35 the strain on the necks of the animals.

Having described my invention, what I claim, and desire to secure by Letters Patent, is—

In coupling bolsters with axles of wagons, the combination, with axle-plate C, adapted to 40 be secured to axle A, and having wearing-face a , convex projection b , and annular step c , of chilled iron, and bush d , with king-bolt hole e , of the bolster-plate D, adapted to be secured to axle B, and having wearing-face a' , concave 45 recess b' , and recessed annular step c' , of chilled iron, and bush d , with king-bolt hole e' , adapted to be held together by king-bolt E, passing through said bolster-plates, and axle, substantially as and for the purposes set forth. 50

THOS. VAN AERNAM.
